UNITED STATES PATENT OFFICE

WILLIAM BATES LUCAS, OF EAST ORANGE, NEW JERSEY, ASSIGNOR TO OTIS ELEVATOR COMPANY, OF NEW YORK, N. Y., A CORPORATION OF NEW JERSEY

FLASH LIGHT ANNUNCIATOR

Application filed January 8, 1929. Serial No. 331,125.

This invention relates to signal annunciator systems, useful, for example, for elevators.

One feature of this invention is the provision of a flashlight annunciator with the electromagnetic control switches therefor contained within the indicator casing.

A second feature of this invention is the provision of a plurality of electromagnetically controlled latching switches operable individually to move the switches in one direction but operable collectively to move the switches in the opposite direction, each of said switches having only one actuating coil and utilizing only a single impulse of current for each controlling operation.

Other features and advantages will become apparent from the specification, taken in conjunction with the accompanying drawings wherein one embodiment of the invention is illustrated.

The invention involves a plurality of flashlight bulbs positioned in a suitable indicator or display casing, electromagnetically controlled switches also positioned for simplicity and compactness in said casing, and circuits arranged so that momentary operation of remotely positioned signal buttons control the switches to light and retain illuminated the flashlight bulbs corresponding to the operated signal buttons until the actuation of a single reset button adjacent the casing, when all the illuminated bulbs are collectively extinguished. The invention further involves using, as the electromagnetically controlled switches above described, a plurality of latching switches the operation of each of which from either one of its positions to the other is initiated by the full energization of a single actuating coil, each latching switch being constructed and connected to automatically deenergize its actuating coil after movement of its switch arm from its initial position to permit the switch arm to continue its movement to its final position. It also involves connecting the flashlight bulb as a resistance in series with the actuating coil of its respective latching switch when that bulb is caused to be illuminated by that switch, the resistance of the bulb being such that the actuating coil is insufficiently energized to cause operation

of the switch. It also involves short-circuiting the bulb, thereby removing the resistance in the circuit of the actuating coil and increasing the current flowing therethrough, to cause the bulb-extinguishing operation of that latching switch.

The invention still further involves an extra contact on all the signal buttons to complete a circuit independent from the latching switch circuits and including a buzzer so that the buzzer is responsive to any operation of the signal buttons.

In the drawings:

Figure 1 is a front elevation of a flashlight annunciator embodying this invention, with parts broken away to show certain details of the interior thereof;

Figure 2 is a section thereof taken along the line 2—2 of Figure 1;

Figure 3 is a side elevation thereof with parts broken away to show certain details;

Figure 4 is a section of the reset push button taken along the line 4—4 of Figure 3;

Figure 5 is an enlarged view of the latching switch and flashlight support taken along the line 5—5 of Figure 1, showing the position of the movable parts thereof when the controlled flashlight bulb is illuminated;

Figure 6 is a side view of the switch as shown in Figure 5;

Figure 7 is a view from the rear of the switch as it is shown in Figure 5, showing the initial position of the movable parts thereof before the controlled flashlight bulb is illuminated; and

Figure 8 diagrammatically shows some of the latching switches that are used in the flashlight annunciator of this invention, and an arrangement of connections therefor.

Referring to Figures 1 to 3, inclusive, casing 11 houses the complete switch control and indicator apparatus of a flashlight annunciator system with the exception of the power supply and the remotely positioned signal buttons. The apparatus housed by the casing includes single-coil latching switches 13, flashlight bulbs 14 (there being one latching switch and one bulb for each signal push button in the annunciator system), buzzer 15, and reset push button 16. The casing is pro-

vided with a cover plate 12 which is slotted for part of its length. Mounted within the opening formed by the slot is a glass strip 17 through which light from the illuminated bulbs in the rear of the strip may pass. Numbers or other signals may be arranged in any suitable manner to be displayed through the glass upon the illumination of the bulbs. In the annunciator as shown the glass is coated on its inside surface, except for the outlines of the numbers, with an opaque substance so that only the numbers behind which bulbs are illuminated are visible. This is illustrated by the number 3 for the third floor.

The single coil latching switch designated generally by 13 is clearly shown in Figures 5, 6 and 7, and is described and claimed in copending application Serial No. 317,977, filed November 8, 1928. According to the preferred construction of this switch, the various parts thereof are mounted on a support 35 which may be a copper-plated sheet steel stamping. This support has stepped fastening ends 38, two contact supporting portions 36 and 37, and a connecting cross-piece 39 with extensions 40 and 41, the former for a bearing support and the latter for a coil support. In addition, coil support 41 has a lip extension 42 for another bearing support. The legs of a U-shaped armature 43 are adjacent the two bearing supports, and are pivotally mounted thereon by the long pin 44 which extends between the two bearing supports and through an oversize hole (not shown) in the coil support. One leg of the armature engages with the edges of the contact-supporting portions 36 and 37 alternately, as the armature is swung to and fro, which portions thereby function as stops to limit the motion of the armature (see Figure 7). An operating coil 46 is secured to the coil support 41 so that the end of its core 47 is adapted to attract the yoke of the armature from either extreme position to a position midway between the two extremes. The terminals for the coil are indicated by reference character 57.

Mounted upon contact-supporting portion 36 of stamping 35 by the machine screws 50 is the metallic contact plate 51 to which is affixed the contact 52. Similarly mounted upon contact-supporting portion 37 is metallic contact plate 53 to which is affixed the contact 54. Both contact strips are insulated from the sheet steel stamping by means of the insulating strips 55 which are placed on both sides of the contact-supporting portions of the stamping, and both contact strips have terminal-connecting portions 56 to which leads may be attached, as by soldering.

A metallic switch lever 58 is pivotally supported upon pin 44 between extensions 40 and 41 and with its lower surface below the pin.

This lower surface has affixed thereto a contact 62 which engages with the stationary

contact 52 when the switch lever is in one extreme position, and also a contact 64 which engages with the stationary contact 54 when the switch lever is in the other extreme position. A portion 59 of the switch lever extends above the pin and rotatably supports a toggle link 60, the outer end of which extends through an opening 61 in the yoke of the armature. A spring 63 under compression surrounds the toggle link, and presses at one end against the underside of the armature yoke and at the other end against a shoulder on the toggle link. Washers 65 may be used to separate the moving parts from the stationary parts.

It is to be noted that when the parts are in the position as shown in Figure 7, a torque resulting from the force of the spring and the displacement of the toggle link pivot out of the plane through pin 44 and opening 61, hereinafter referred to as the plane of the armature, urges the switch lever clockwise and the armature counterclockwise, thereby maintaining contacts 52 and 62 in engagement, and one leg of the armature against the stopping edge of portion 36.

From the positions of the parts as shown in Figure 7, let the armature be moved clockwise until the armature is in a position where the yoke is a small distance past the center of the core, that is, until the armature has reached and passed a little beyond its mid-position. This movement further compresses the spring, but reduces the displacement of the toggle link pivot from the plane of the armature until at the above position it is substantially zero, when the torque also is substantially zero. Further clockwise movement of the armature increases the displacement of the toggle link pivot from the plane of the armature, but in the opposite direction, so that the torque is reversed and the switch lever is urged counterclockwise, which moves accordingly, thereby disengaging contacts 52 and 62 and engaging contacts 54 and 64. In addition, the spring urges the armature over to the extreme clockwise position with the armature leg against the stopping edge of portion 37. At the termination of the movements, the parts are as shown in Figure 5, which figure, it is to be recalled, is from the direction opposite to that of Figure 7.

The operation of the parts in the reverse direction being analogous to the operation above described, it is for conciseness omitted. It is to be noted that in either case, however, the armature need only be moved to a little past the mid-position, from which point the completion of movements of the parts of the switch is effected automatically. It is also to be noted that after each operation of the switch the parts are maintained in their new positions by the action of spring 63.

Contact plate 53 of each latching switch is extended as at 66 to form a support for, and

a connection to, a lamp socket 67. This socket is secured to extension 66 by the machine screw 68, the head of which forms the center contact of the socket. The metallic shell of the socket is insulated from screw 68 and extension 66 by washers 70 and 71. Connection to the shell is obtained by a lug 72 in contact therewith. Into each socket 67 a bulb 14 is screwed so that each latching switch controls the illumination of a corresponding electric light bulb.

The latching switches are mounted within casing 11 on the insulating base 18 by means of the machine screws 49 so that the bulbs are behind glass strip 17, as shown in Figure 1. Screws 49 also secure the bent edges 73 of light shields 74. These shields extend from the base of the casing adjacent stepped fastening ends 38 of each latching switch to the glass strip 17. As a result of this construction, the area in rear of the glass strip is divided into sections, one corresponding to each latching switch and bulb, so that the illumination of any one of the bulbs is confined to the corresponding area of the glass strip 17.

At the lower end of the casing is mounted the reset push button 16 with the manual push button proper 20 extending through a hole in the cover plate. A spring 21 is compressed between the rear of the button proper and a bracket 22 to maintain the contacts of the button normally open. A metallic plug 23 has one of its ends secured to the rear of the button. About the other end are grouped a plurality of spring fingers 24 insulated one from another and mounted upon the insulating base 25. The button is designed so that when it is depressed the end of the metallic plug 23 engages with all of the spring fingers and makes contact therewith. Normally, there is a spring finger for each latching switch 13 and one extra finger.

A terminal strip 75 may be provided for the convenient connection of the external circuits to the annunciator.

Figure 8 illustrates diagrammatically a preferred arrangement of connections for the latching switches and flashlight annunciator. Each numeral immediately to the right of the minus lead indicates the floor for which the apparatus that is shown at the corresponding level is provided. In order to simplify the diagram, the apparatus for the second, third and fourth floors has been omitted. This figure shows the conditions of the annunciator circuits for the annunciator as illustrated in Figure 1 in which the bulbs for the third and fifth floors are illuminated.

Considering the circuit connections in detail, one terminal of each operating coil 46 is connected to one supply lead, as the plus, while the other terminal of each operating coil is connected to its respective switch lever. This may be accomplished in the design

of the switch shown by connection to the respective fastening ends 38 of each latching switch, or, if desired, by connection directly to the respective switch levers. Contacts 54 are already connected by extensions 66 to the respective bulbs. The other terminals of the bulbs obtained by lugs 72 are connected to the other supply lead, as minus. From each contact 52, a connection is made to the contact 31 of its respective signal push button 30. From each of the second signal push button contacts 32 connection is made to the minus side of the supply, while each of the third signal push button contacts 33 is connected to a common lead 34 which terminates at one side of buzzer 15. The other side of the buzzer is connected to the plus lead of the supply.

Across each bulb 14, from the minus lead to the respective contact 54 there are connected individual reset contacts 26, all of said individual reset contacts being operable collectively by the manual push button 20. The expanded arrangement of the reset push button circuits as shown in Figure 8 is diagrammatic and tends to simplification. As may be seen, each contact 27 of the individual reset contacts is connected to the respective latching switch contact 54, while each contact 28 of the individual reset contacts is connected to the common minus lead. The physical embodiment of the reset button may therefore be as illustrated in Figures 3 and 4, in which the contacts 27 are embodied in seven spring fingers 24, while all the contacts 28 are embodied in the eighth, or the one extra, spring finger 24. Contact of metallic plug 23 with all eight fingers completes a circuit from the seven fingers corresponding to the contacts 27 to the one finger corresponding to the contacts 28.

It will be understood that the second, third and fourth floor signal circuits which are omitted for simplicity from the diagram of Figure 8 are similar to the floor signal circuits shown.

In operation, let it be assumed that the signal push button 30 at the sixth floor is depressed. A circuit for the operating coil 46 of the sixth floor latching switch 13 is completed, which may be traced from the plus lead, through the operating coil 46, by way of its corresponding contacts 62 and 52, contacts 31 and 32 of the corresponding push button, to the minus lead. The consequent energization of the operating coil results in the attraction of armature 43 from its extreme position, as shown, to the mid-position. Due to its inertia, however, it does not stop in mid-position but continues on past. The spring then operates as previously described to insure the movement of the armature to the other extreme position, to disengage contacts 52 and 62, to engage contacts 54 and 64 and to maintain the parts in these

new positions. The circuit through push button 30 is therefore broken and the operating coil deenergized, thereby permitting the contacts 54 and 64 to remain engaged.

5 The engagement of contacts 54 and 64 completes the circuit for the sixth floor flashlight bulb 14 which may be traced from the plus lead, through the operating coil 46 of the sixth floor latching switch, by way of contacts 64 and 54, through the bulb 14, to the minus lead. The sixth floor flashlight bulb 14 is accordingly illuminated. The position of the floor signal circuit at this stage is similar to the showing of the fifth floor signal circuit.

10 It is to be noted that when a flashlight bulb is illuminated, the current therefor goes through the winding of the operating coil 46 of the corresponding latching switch. Due to 15 the resistance of the flashlight bulb, the magnitude of this current is therefore less than that obtained when the winding is connected directly between the plus and minus leads. As a result, the attractive force of the operating coil core is not sufficient, when the flashlight bulb is illuminated, to move the armature.

15 To extinguish all the flashlight bulbs 14 that may be illuminated the manual push button 20 is depressed. This completes a shunting circuit around each flashlight bulb, and for those floor signal circuits in which the bulbs are at that time illuminated, establishes a circuit from the plus lead, through the respective operating coils 46, by way of contacts 64 and 54, and contacts 27 and 28, directly to the minus lead. The currents in the windings of those operating coils 46 therefore become of sufficient magnitude to 20 attract their respective armatures to their mid-positions. Due to their inertia, however, they do not stop in mid-position but continue on past. The respective springs then operate in the manner previously described to insure the movement of the armatures to their initial extreme positions, to disengage contacts 54 and 64 of the respective switches, to engage contacts 52 and 62 of the respective switches and to maintain the 25 parts in these new positions. The circuits for the flashlight bulbs 14 that were illuminated before the operation of the reset push button 20 are accordingly broken, and these bulbs extinguished. The latching switches which 30 already have their contacts 62 and 52 engaged, and therefore their corresponding flashlight bulbs 14 unilluminated, are not affected by the operation of the reset button 20. At the completion of the reset movements, all 35 flashlight bulbs are extinguished and all latching switches are in position to be responsive to the floor signal push buttons.

40 It is to be noted that after a floor signal push button has been depressed and the corresponding latching switch has operated to

illuminate the corresponding flashlight bulb, continued or subsequent depression of the same floor button has no effect upon the latching switch.

45 It may be desirable, in certain installations, to include a buzzer with the flashlight annunciator, so Figure 8 illustrates also an arrangement of connections for a buzzer when it is so desired to use it in conjunction with this flashlight annunciator. The floor signal push buttons have a third contact 33, each of which is joined to a common lead 34 which connects with the plus lead through the buzzer 15. When the floor buttons are depressed, in addition to operating the latching switches as previously described, a circuit from the plus lead, through the buzzer by way of common lead 34 and contacts 33 and 32 to the minus lead, is completed, and the buzzer 50 operates. It is to be noted that the buzzer 55 may be operated after the operation of the latching switches to signal a dormant operator. It is apparent that if it should be desired to have the buzzer operate during certain periods of the day, and to be disabled 50 at other periods, a switch may be inserted in the buzzer circuit to close and open this line.

55 Although the construction of the single coil latching switch illustrated is a preferred 95 form, it is to be understood that single coil latching switches, constructed in other forms but basically similar in operation, may be used if desired.

60 As many changes could be made in the 100 above construction and many apparently widely different embodiments of this invention could be made without departing from the scope thereof, it is intended that all matter contained in the above description or 105 shown in the accompanying drawings shall be interpreted as illustrative and not in a limiting sense.

65 What is claimed is:

70 1. A flashlight annunciator comprising; a 110 casing; a cover plate therefor provided with a plurality of signal indications displayable therethrough upon illumination within said casing; a plurality of signal bulbs mounted in said casing to illuminate said signal indications, said signal bulbs being arranged to illuminate corresponding signal indications; a plurality of switches, one for each signal bulb, positioned within said casing, each switch comprising a single actuating coil, an 75 armature cooperating therewith, a switch arm movable to a closed-switch position to illuminate the corresponding signal bulb and to an open-switch position to extinguish said corresponding signal bulb, mechanism cooperating with said armature and said switch arm for moving said switch arm alternately from either the open-switch or the closed-switch position to the other switch position upon successive switch-actuating energiza- 80 120 125

- tions of said single actuating coil; means individual to each switch operable to energize the single actuating coil of the corresponding switch to thereby illuminate the corresponding signal bulb; and means local to said casing and in part common to all of said switches to collectively extinguish all of said signal bulbs.
2. An electromagnetically controlled device comprising, a single actuating coil, an armature cooperating therewith, two stationary contacts, a switch arm movable to engage either of said two stationary contacts to the exclusion of the other, mechanism cooperating with said armature and said switch arm for moving said switch arm, upon successive switch-actuating energizations of said single actuating coil, alternately from engagement with one stationary contact to engagement with the other stationary contact, a source of electrical energy, connection from one terminal of said single actuating coil to one terminal of said source of supply, connection from the other terminal of said single actuating coil to said switch arm, an impedance connected at one end to one of said stationary contacts and at the other end to the second terminal of said source of supply, and two circuit-closing switches, one of said switches, when operated, closing a circuit between the second stationary contact and the second terminal of said source of supply, and the other of said switches, when operated, short-circuiting said impedance.
3. An electromagnetically controlled light signal comprising, a bulb, a source of electrical energy, two stationary contacts, connection from one contact to one terminal of said bulb, connection from the second terminal of said bulb to one terminal of said source of supply, two circuit-closing buttons, one button being connected between the second of said stationary contacts and said first terminal of said supply, and the second button being connected between said first of said stationary contacts and said first terminal of said supply; a switch arm movable to engage either of said two stationary contacts to the exclusion of the other, a single magnet coil, connection from one terminal of said magnet coil to said switch arm, connection from the second terminal of said magnet coil to the second terminal of said source of supply, an armature in operative relation to said magnet coil, and mechanism cooperating with said armature and said switch arm for moving said switch arm alternately from engagement with one stationary contact to engagement with the other stationary contact upon alternate operation of the circuit-closing buttons to successively energize said single magnet coil, with the result that operation of the first button effects illumination of said bulb and that subsequent operation of the second button effects extinguishment of said bulb.
4. In combination; a plurality of electromagnetically controlled switches; each switch comprising, a single actuating coil, an armature cooperating therewith, two stationary contacts, a switch arm movable to engage either of said two stationary contacts to the exclusion of the other, and mechanism cooperating with said armature and said switch arm for moving said switch arm alternately from engagement with one stationary contact to engagement with the other stationary contact upon successive switch-actuating energizations of said single actuating coil; means individual to each switch operable to individually control the movement of the corresponding switch arm from engagement with one of said stationary contacts as an initial position to engagement with the other of said stationary contacts as a second position; and means in part common to all of said switches operable to collectively move all of said switch arms which may be in said second position to said initial position.
5. In combination; a plurality of electromagnetically controlled switches; each switch comprising, a single actuating coil, an armature cooperating therewith, a switch arm movable to closed-switch and to open-switch positions, and mechanism cooperating with said armature and said switch arm for moving said switch arm alternately from either the closed-switch or open-switch position to the other switch position upon successive switch-actuating energizations of said single actuating coil; means individual to each switch operable to individually control the movement of the corresponding switch arms from their open-switch positions to their closed-switch positions; and means in part common to all of said switches operable to collectively restore all of said switch arms from their closed-switch positions to their open-switch positions.
6. In combination; a source of electrical energy; a plurality of individual loads; and electric control means operable to individually connect said loads to said source of supply and to collectively disconnect said loads from said source of supply, said means comprising, a pair of load contacts for each load, a pair of control contacts for each load, a switch arm for each load movable to cause the engagement of either one or the other of the corresponding two pairs of contacts and to cause disengagement of the remaining pair of the corresponding two pairs of contacts, a single magnet coil for each load, an armature for each load cooperating with the corresponding magnet coil, mechanism cooperating between each armature and each corresponding switch arm for moving said corresponding switch arm to cause alternate engagement of the corresponding pair of load contacts and of the corresponding pair of control contacts upon

successive armature-actuating energizations of the corresponding magnet coil, a plurality of load-connecting controls, each load-connecting control to be adapted to cause the 5 operation of a corresponding switch arm to engage the corresponding pair of load contacts, connection from one contact of each pair of load contacts to one side of the source of supply by way of 10 the corresponding magnet coil for each pair of load contacts, connection from the other contact of each pair of load contacts to the second side of the source of supply by way of the corresponding load for each pair of load 15 contacts, connection from one contact of each pair of control contacts to said one side of the source of supply by way of the corresponding magnet coil for each pair of control contacts, connection from the other contact 20 of each pair of control contacts to said second side of the source of supply by way of the corresponding load-connecting control for each switch arm, and a load-disconnecting control operable to collectively shunt each 25 load.

7. In a flashlight annunciator, a plurality of signal bulbs; a source of electrical energy; and electric control means operable to individually connect said signal bulbs to said 30 source of supply and to collectively disconnect said signal bulbs from said source of supply, said means comprising, a pair of stationary contacts for each signal bulb, a switch arm for each signal bulb movable to engage either contact of said pair of stationary contacts for the corresponding signal bulb to the exclusion of the other of said stationary contacts, a single magnet coil for each signal bulb, an armature for each signal bulb cooperating with the corresponding magnet coil, 35 each of said armatures being pivoted so as to swing across the core face of said magnet coil from either one of two limiting positions of said armature to the other of said limiting positions, means for effecting movement of each of said switch arms to cause the engagement of each thereof with one of the stationary contacts provided therefor when the armature for the corresponding signal bulb is in one of its limiting positions, and with 40 the other of the stationary contacts provided therefor when the armature for the corresponding signal bulb is in the other of its limiting positions, and for normally retaining each of said armatures in either of its limiting positions when the magnet coil corresponding thereto is not energized, with an armature actuating current, a plurality of annunciator buttons, one button for each signal bulb, each annunciator button having three 45 contacts normally insulated from each other but which are electrically connected upon operation of the annunciator button, a connection from one side of the source of supply to each switch arm by way of the corresponding magnet coil for said switch arm, a connection from one of the stationary contacts for each of said switch arms to the second side of the source of supply by way of the signal bulb for which said switch arm and its 50 corresponding stationary contacts are provided, a connection from the other of the stationary contacts for each of said switch arms to one of the contacts of the annunciator button for the signal bulb for which the switch arm is provided, a connection from a second contact of each annunciator button to the second side of the source of supply, and a reset device operable to collectively shunt each signal bulb; a buzzer provided for said 55 60 65 70 75 80 85 90 95 100 105 110 115 120 125 130

nunciator system; a connection from one terminal of said buzzer to said first mentioned side of the source of supply; and a connection from the other terminal of said buzzer to the
5 third contact of each annunciator button.

In testimony whereof, I have signed my name to this specification.

WILLIAM BATES LUCAS.
